CLAIM

The ornamental design for a net with suction cup handle, as shown and described.

DESCRIPTION

FIG. 1: is a front elevation view for a net with suction cup handle according to my new design;

FIG. 2: is a back elevation view thereof;

FIG. 3: is a left elevation view thereof;

FIG. 4: is a right elevation view thereof;

FIG. 5: is an enlarged bottom view thereof;

FIG. 6: is enlarged top view thereof; and,

FIG. 7: is a perspective view thereof.

The design of the net with suction cap handle provides suction to a flat surface to hold the net and handle in place. The net frame is rectangle in shape to collect debris. The handle is cylinder shape to grab and hold and is attached to the net. The suction cup is cone shape and attached to the handle.
